OVERCAP FOR A DISPENSING CLOSURE

Stanley K. Johns, 588 Linwood Ave.,
Buffalo, N.Y. 14209

Filed Aug. 17, 1964, Ser. No. 81,298

Term of patent 14 years

(Cl. D58—26)

FIG. 1.

FIG. 2.

FIG. 3.

FIG. 4.

FIG. 6.

FIG. 8.

FIG. 5.

FIG. 7.

FIG. 9.

FIG. 10.

FIG. 1 is a perspective view, on an enlarged scale, of an overcap for a dispensing closure, showing my new design thereof;

FIG. 2 is a top plan view thereof;

FIG. 3 is a front elevational view thereof;

FIGS. 4 and 5 are opposite side elevational views thereof;

FIGS. 6 and 7 are top plan and side elevational views of an overcap for a dispensing closure showing a modification of my design wherein the side walls are serrated; and

FIGS. 8 and 9 are top plan and side elevational views of an overcap for a dispensing closure showing a modification of my design wherein the side walls are fluted; and

FIG. 10 is a vertical section taken on line 10—10 of FIG. 2 showing the interior of the overcap for a dispensing closure.

I claim:

The ornamental design for an overcap for a dispensing closure, substantially as shown and described.
